UNITED STATES PATENT OFFICE.

WILLIAM J. PATTERSON AND ALFRED M. ACKLIN, OF PITTSBURG, PENNSYLVANIA, ASSIGNORS TO HEYL AND PATTERSON, OF PITTSBURG, PENNSYLVANIA, A COPARTNERSHIP.

SAFETY DEVICE FOR CAR-HAULS.

SPECIFICATION forming part of Letters Patent No. 768,191, dated August 23, 1904.

Application filed November 2, 1903. Serial No. 179,519. (No model.)

To all whom it may concern:

Be it known that we, WILLIAM J. PATTERSON and ALFRED M. ACKLIN, residents of Pittsburgh, in the county of Allegheny and State of Pennsylvania, have invented a new and useful Improvement in Safety Devices for Car-Hauls; and we do hereby declare the following to be a full, clear, and exact description thereof.

10 Our invention relates to a safety device for car-hauls.

The object of our invention is to provide an efficient form of safety device by means of which the chain of the car-haul on the ascent will be checked or held from slipping down in case of a break in the chain or driving-gear.

Our invention comprises, generally stated, in conjunction with a traveling chain or cable 15 and its sprocket-wheels, means for preventing the backward movement of the ascending portion of said chain in case said chain should break.

To enable others skilled in the art to make 20 and use our invention, we will describe the same more fully, referring to the accompanying drawings, in which—

Figure 1 is a diagrammatic view of a car-haul to which our invention is applicable. 25 Fig. 2 is an enlarged side view of a portion of car-haul chain with our invention applied thereto. Fig. 3 is a plan view of same. Fig. 4 is a view of the brake-band.

Like numerals indicate like parts in each 30 of the figures.

The numeral 2 designates a suitable chain or cable to which the cars are connected in any suitable manner for the purpose of drawing said cars up the ascent to the point of 35 discharge. The chain 2 passes around the sprocket-wheels 3 4 at the top and bottom of the haul, respectively, the upper wheel 3 being power-driven. Mounted within suitable bearings 5 in the frame 6 is the shaft 7. A 40 sprocket-wheel 8 is secured to the shaft 7, said wheel having the recesses 9 between its teeth, and within these recesses the inner links 10 of the chain enter. The outer links 11 of

said chain have a space between them into which the teeth of the sprocket-wheel 8 enter. 50 Preferably formed integral with the sprocket-wheel 8 is the circular ratchet-face 12. Pawls 13 14 are adapted to engage this ratchet-face 12, said pawls being secured to the shafts 15 and 16, respectively. The longer pawl 14 is 55 just back of and in line with the shorter pawl 13, so that when the shorter pawl is thrown out of engagement it also throws out the pawl 14. A stop 17 regulates the movement of 60 said pawls.

The shaft 15, on which pawl 13 is mounted, is journaled in the frame, and to its opposite end is secured the arm 18. The opposite end of the arm 18 is connected to the brake-band 19, which passes over the brake-wheel 20. 65 This band 19 is lined with wooden blocks 21, adapted to conform to the circumference of the brake-wheel, and to the free end of said brake-band is secured the weight 22. This weight 22 may be made up of a series of 70 washers, so that its weight may be increased or diminished, as desired.

If in the operation of the car-haul the chain 2 is driven to ascend in the direction of the arrow, the cars attached thereto will also be 75 carried up the haul. The sprocket-wheel 8 will be driven in the direction of the arrow and also the brake-wheel 20 on the same shaft. The rotation of brake-wheel 20 will create a 80 pull on brake-band 19, which will act to lift arm 18. The lifting of arm 18 will act to throw out the pawl 13, and consequently pawl 14. These pawls will be held out of engagement with the ratchet-face 12 as long as 85 the brake-wheel continues to rotate in this direction. If, however, the chain 2 should break at a point above the sprocket-wheel 8, the said sprocket-wheel will cease to rotate in direction indicated, and a force will be exerted to pull it in the opposite direction. 90 However, immediately the break occurs the pull on brake-band 19 ceases, and the arm 18 is lowered and pawls 13 14 allowed to drop into engagement with ratchet-face 12. The backward movement of the sprocket-wheel 8 95 is checked, and as the teeth of said wheel pro-

ject up between the links of the chain 2 the further slipping or descent of the chain is prevented.

It is apparent that our invention may be applied with effect to the main power-shaft, so that when the power is cut off for any reason with a number of loaded cars engaging the chain on the ascent the pawls will engage the ratchet-wheel on the power-shaft and tend to relieve the strain due to the backward pull occasioned by the weight of the loaded cars upon the chain. We do not wish to limit our invention to the construction illustrated, as that may be varied without affecting the scope 15 of our invention.

What we claim is—

1. In a safety device for car-hauls, the combination with a power-driven endless chain, of a sprocket-wheel intermediate the ends of 20 said haul engaged by said chain, and means for preventing the rotation of said sprocket-wheel in the opposite direction from the travel of said chain.

2. In a safety device for car-hauls, the combination with a power-driven endless chain, of a sprocket-wheel adjacent to the sprocket-wheel at the upper end of said car-haul, said first-named sprocket-wheel being engaged by 25 said chain, and means for preventing the rotation of said sprocket-wheel in the opposite direction from the travel of said chain.

3. In a safety device for car-hauls, the combination of a ratchet-wheel, a pawl adapted to engage therewith, a second pawl in the rear 30 of said first-named pawl and in line therewith, and means for holding said first-named pawl out of engagement with said ratchet-wheel.

4. In a safety device for car-hauls, the combination of a ratchet-wheel, a pawl adapted 40 to engage therewith, a brake-wheel, a brake-band on said brake-wheel, and connections between said brake-band and said pawl, whereby said pawl is held out of engagement during the rotation of said brake-wheel.

5. In a safety device for car-hauls, the combination of a ratchet-wheel, a pawl adapted to engage therewith, a brake-wheel, a brake-band engaging said brake-wheel, and an arm connected to said brake-band and to said pawl. 45

6. In a safety device for car-hauls, the combination of a ratchet-wheel, a pawl adapted to engage therewith, a brake-wheel, a weighted brake-band engaging said brake-wheel, and connections between said brake-band and said pawl, whereby said pawl is held out of engagement 50 with said ratchet-wheel during the movement of said wheel.

7. In a safety device for car-hauls, the combination of a ratchet-wheel, a pawl adapted to engage therewith, a second pawl in the rear 55 of said first-named pawl and in line therewith, a brake-wheel, a brake-band engaging said wheel, and connections between said brake-band and said inner pawl, whereby said inner pawl is held out of engagement by the movement of said wheel.

8. In a safety device for car-hauls, the combination of a suitable sprocket-chain, sprocket-wheels at the upper and lower end of said car-haul engaged by said chain, a sprocket-wheel between said first-mentioned sprocket-wheels and engaged by said chain, a ratchet-wheel, a pawl adapted to engage said ratchet-wheel, a brake-wheel, a brake-band engaging said 65 brake-wheel, connections between said pawl and said brake-band, whereby the said pawl is held out of engagement with said ratchet-wheel during the rotation of said sprocket-wheel. 75

In testimony whereof we, the said WILLIAM 80 J. PATTERSON and ALFRED M. ACKLIN, have hereunto set our hands.

WILLIAM J. PATTERSON.
ALFRED M. ACKLIN.
